UNITED STATES PATENT OFFICE.

RAGNAR CARLSTEDT, OF STOCKHOLM, SWEDEN, ASSIGNOR TO ARCA REGULATORS INCORPORATED, A CORPORATION OF VIRGINIA.

AUTOMATIC HUMIDITY AND TEMPERATURE CONTROL.

Application filed June 19, 1924. Serial No. 721,104.

The present invention relates to an apparatus for conditioning air, and has for its purpose to maintain a definite relation between temperature and humidity and to provide novel means for controlling humidity.

The invention is particularly applicable to drying rooms where a fixed temperature and fixed humidity is necessary. For example, in the tobacco industry, up to the present time it has been impossible to regulate the moisture content and temperature in drying rooms in a satisfactory manner, there being no sufficiently sensitive apparatus for this purpose.

15 The invention is more fully described in connection with the accompanying drawing on which Fig. 1 shows a drying chamber with my invention applied thereto. Fig. 2 shows details of construction of the apparatus shown in Fig. 1.

In Fig. 1, 2 is a drying room, through which air is drawn by the fan 3 which is driven by electric motor 4. At the inlet 5 this air passes a heating element 6 by means 25 of which it is heated to a definite temperature. Arranged in the chamber is a so-called humidity relay 7, shown on an enlarged scale in Fig. 2, consisting of a throttling lever 8 which is movable in front of a nozzle through which a continuously flowing stream of liquid issues and which is connected by means of the pipe 10 with operating mechanism for a servo-motor 11 actuated by a pressure fluid which servo-motor in its 30 turn adjusts a rheostat 12 by which the speed of the motor 4 is varied. This throttling lever is connected with a member 14, which preferably consists of several united parallel cotton threads, adjustably suspended at 35 the point 15 by means of a screw 26. The throttling lever 8, which for the purpose of moving with the least possible friction is journaled on points 16, is also influenced by a spring 17, which is tensed to a greater or 40 less degree by means of the screw 18.

Servo-motor 11 consists of a piston 21 to which is attached piston rod 23. A flexible member 22, such as a chain, is connected at one end of the piston rod 23 and at the other 45 end to a counterweight 24, and operates to actuate the rheostat 12. By means of a pipe

51 the servomotor is connected with actuating means for the same 45, which comprises a pilot valve 46 connected to a diaphragm 47 and acted upon by a spring 48; between 55 the pilot valve 46, diaphragm 47 and the housing of the actuating means 45 is a diaphragm chamber 52 which is connected with nozzle 9 by means of pipe 10. The pilot valve operates to connect the servo-motor 60 either with a supply conduit 49 for liquid under pressure or a drain conduit 50. Connecting pipe 10 with pipe 49 is a branch pipe 35 containing a restriction 36 of much smaller area than the orifice of nozzle 9.

Fig. 2 shows the relay 7 on enlarged scale, and it may be clearly seen therefrom how the member 14 is assembled of several and interconnected threads 30. In order that all the threads co-operate it is necessary that all 70 be under uniform tension, and the best method of constructing the strand is by winding the desired number of turns on two parallel combs, and attaching a rubberized linen strip about both ends of the strand. 75 By this means the interval between the threads and their distance is accurately maintained, and the strand may easily be mounted in the clamps 25. The upper clamp is attached by means of the screw 26 to the 80 nut 27, thus rendering possible an easily accessible, accurate adjustment of the regulating device.

For regulating the temperature of the air flowing through the room, a so-called 85 thermo relay 37 is provided, which is shown at operating servo-motor 38. This operation may be the same as with the humidity regulator. By means of the restriction 39, pressure changes in pipe 53 cause pressure 90 changes in the servo-motor which actuates valve 32 mounted in the steam pipe 31 leading to the heating element 6. In the thermo relay a strip of ebonite 54 is used in place 95 of the cotton threads 14 of the humidity relay.

The operation of the apparatus is as follows:—

Suppose, for example, the room 2 is filled with wood to be dried. At first a great deal 100 of moisture is given off by the wood, as a result of which the humidity in the room in-

- creases. This shortens the length of the threads 14 thereby moving throttling member 8 away from nozzle 9. This increases the flow of liquid through the nozzle and 5 decreases the pressure in pipe 10 and consequently in diaphragm chamber 52. This decrease in pressure is made possible by restriction 36 in the supply pipe leading to pipe 10. A decrease of pressure in chamber 10 52 causes downward movement of pilot valve 46 under action of spring 48 so that the servo-motor 11 is connected with discharge pipe 50. Counterweight 24 then outbalances pressure of liquid in the servo-motor and 15 rotates rheostat 12 to increase the speed of fan 3 in order to hold the humidity constant. Now, when the speed of fan 3 is increased, the amount of air passing by and heated by the radiator 6 is also increased, so 20 that the temperature of the same falls. This causes the temperature regulator to come into operation by decreasing the length of the temperature responsive element 54, thereby decreasing the pressure in pipe 53 and 25 moving valve 32 to open the same. More steam is then admitted to the heating element 6 and the temperature of the air increased. As the wood becomes drier the amount of moisture given off is progres- 30 sively less and less and the humidity relay causes the speed of fan 3 to decrease proportionally. This causes the air passing through heating element 6 to diminish in similar manner and the thermo relay oper- 35 ates to decrease the flow of steam in proportion. Thus in operation constant humidity and constant temperature are maintained, and as the humidity is altered the temper- ature is altered accordingly. 40 Specific parts of the relay herein disclosed are claimed in my copending application Serial No. 719,022, filed June 9, 1924.
- Having thus described my invention, what I claim is:
- 45 1. In combination, a temperature and humidity controlling apparatus comprising a relay, means to discharge a continuously flowing stream of liquid into said relay, means to control said stream of liquid in re- 50 sponse to humidity, means whereby said stream of liquid controls a current of air, a second relay, means to discharge a continuously flowing stream of liquid into said second relay, temperature responsive means to control said second stream of liquid and means whereby the last mentioned continuously flowing stream of liquid controls the temperature of said current of air.
- 55 2. In combination, a room, means to pass air through said room, liquid pressure operated means to control said means, a mechanism including a continuously flowing stream of liquid to control said liquid pressure operated means, a humidity responsive device responsive to changes of humidity in

the air passing thru the room to control said continuously flowing stream of liquid, a heating element arranged to heat the air passing thru said room, liquid pressure operated means to control said heating ele- 70 ment, mechanism including a continuously flowing stream of liquid to control the last-mentioned liquid pressure operated means, and a temperature responsive device operating in accordance with changes of tem- 75 perature in the air passing thru said room to control the last mentioned continuously flowing stream of liquid.

3. In combination, a chamber, a fan for passing air thru said chamber, an electric 80 motor to drive said fan, a rheostat to control said motor, a liquid pressure operated servo-motor to control said rheostat, a relay, means to discharge a continuously flowing stream of liquid in said relay, a lever to 85 control said continuously flowing stream of liquid, a series of humidity responsive elements responsive to changes of humidity in the air passing thru the chamber to operate said lever, a heating element arranged to 90 heat the air passing thru said chamber, and means to control said heating element in response to changes in temperature in the air passing thru said chamber.

4. Humidity control apparatus comprising 95 a relay, means to discharge a continuously flowing stream of liquid into said relay, a member to throttle said stream of liquid, a series of humidity responsive elements to operate said member, and means controlled 100 by changes of pressure in said stream of liquid to regulate humidity.

5. Humidity control apparatus comprising 105 a relay, a conduit discharging a continuously flowing stream of liquid into said relay, a member to throttle said stream of liquid, an element changeable in response to variations in humidity acting on said member and means controlled by changes of pressure in said stream of liquid to regulate 110 humidity.

6. Humidity control apparatus comprising 115 a fan, an electric motor to drive said fan, a rheostat to control said motor, a relay, a conduit discharging a continuously flowing stream of liquid into said relay, a member responsive to changes in humidity to throttle 120 said stream of liquid, and means to adjust said rheostat in response to changes of pressure in said continuously flowing stream of liquid.

7. Humidity control apparatus comprising 125 a relay, means to discharge a continuously flowing stream of liquid into said relay, a member to throttle said stream of liquid, an element changeable in response to variations in humidity acting on said member; means to adjust said element to vary the relation of said member to said stream of liquid for a given value of humid- 130

ity, and means controlled by changes of pressure in said stream of liquid to regulate humidity.

8. A room, a fan operating to pass a current of air through said room, a rheostat to control said fan, a humidity responsive device and a liquid pressure operated member

controlled by said humidity responsive device to adjust said rheostat in accordance with changes in humidity.

10

In testimony whereof I hereunto affix my signature.

RAGNAR CARLSTEDT.
